Primary Examiner—Ian Simmons*Assistant Examiner*—Carissa C Fitts*(74) Attorney, Agent, or Firm*—Wesley W. Muller(57) **CLAIM**

The ornamental design for an area light, as shown and described.

DESCRIPTION

FIG. 1 is a front perspective view of an area light according to the present invention;

FIG. 2 is a right side view of the area light of FIG. 1;

FIG. 3 is a left side view of the area light of FIG. 1;

FIG. 4 is a top view of the area light of FIG. 1;

FIG. 5 is a bottom view of the area light of FIG. 1;

FIG. 6 is a front view of the area light of FIG. 1; and,

FIG. 7 is a rear view of the area light of FIG. 1.

The broken lines in the figures merely illustrate the environment for the area light of the present design and therefore form no part of the claimed design.
